UNITED STATES PATENT OFFICE.

BERNHARD DREYFUS, OF NEW YORK, N. Y.

DESIGN FOR A PENDANT.

SPECIFICATION forming part of Design No. 15,766, dated February 3, 1885.

Application filed November 26, 1884. Term of patent 7 years.

To all whom it may concern:

Be it known that I, BERNHARD DREYFUS, residing at New York, in the county and State of New York, have invented and produced a new and original Design for Pendants, of which the following is a full, clear, and exact description.

Reference is to be had to the accompanying drawings, forming a part of this specification, in which similar letters of reference indicate corresponding parts in both the figures.

Figure 1 is a face view of my new design for pendants. Fig. 2 is a sectional plan view of the same, taken on the line $x-x$, Fig. 1.

15 The design consists in a central core, A, having a circular cross-section, and tapered from the middle toward both ends, and provided with a slung ruff or tuft, B, at each end.

20 C are longitudinal pieces tapered from the middle toward both ends on the outer surface of the core. The surface of the core shows between the pieces C. The pieces C have a fuzzy appearance.

D is a loop on the upper end of the core,

and E are two beads or balls depending from 25 the lower end of the core by cords F.

I claim—

1. The herein-described design for pendants, consisting of a core tapered from the middle toward each end, and longitudinal pieces tapered from the middle toward the ends on the surface of the core, as shown.

2. The herein-described design for pendants, consisting of a core tapered from the middle toward both ends, a tuft on each end of the 35 core, and longitudinal pieces tapered from the middle toward the ends on the core, as shown.

3. The herein-described design for pendants, consisting of a core tapered from the middle toward each end, and having a tuft on each 40 end, beads depending from the lower end, and pieces tapered from the middle toward the ends on its outer surface, as shown.

BERNHARD DREYFUS.
